DEFENSIVE PUBLICATION

UNITED STATES PATENT AND TRADEMARK OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent and Trademark Office makes no assertion as to the novelty of the disclosed subject matter.

INTEGRATED ABD ALGORITHM

This is a system for accepting the specification of the elements of a block graph which are introduced as input to a computer system and automatically producing paginated block diagrams as output. A set of heuristic procedures are used in this system, which results in an integrated, interactive relationship between the partitioning, placement and line routing functions.
